UNITED STATES PATENT OFFICE.

ALBERT L. SESSIONS, OF BRISTOL, CONNECTICUT.

ROLLER-FRAME.

SPECIFICATION forming part of Letters Patent No. 755,055, dated March 22, 1904.

Application filed September 8, 1903. Serial No. 172,220. (No model.)

To all whom it may concern:

Be it known that I, ALBERT L. SESSIONS, a citizen of the United States, residing at Bristol, Hartford county, Connecticut, have invented certain new and useful Improvements 5 in Roller-Frames, of which the following is a clear, full, and exact description.

My invention relates to an improvement in roller-frames, particularly such as are designed for placing upon the bottoms of trunks and other like articles.

The object of my invention is to simplify, cheapen, and improve the construction of such devices, and particularly to stiffen and 15 strengthen the ears to resist lateral strains.

My invention will be defined in the claims.

The accompanying drawings illustrate my invention embodied in simple and preferred forms.

Figure 1 is an end elevation of one form of my device, showing the roller in place. Fig. 2 is a side elevation of the same device, also showing the roller. Fig. 3 is a bottom plan view of the same device, the roller being omitted. Figs. 4 and 5 are respectively a sectional end and a side elevation of a modified form of device, the section of Fig. 4 being on line 4 4 of Fig. 5. Fig. 6 is a top plan view of the same form of device.

I will first describe the construction shown in Figs. 1, 2, and 3. This roller-frame is preferably but not necessarily formed out of a sheet of metal which is cut to proper form and the parts bent and struck up into the desired shapes. This frame has a base-plate B, from which extend downwardly roller-ears E and E', one at each side of the base and preferably centrally located relative to the length of the base. These roller-ears are preferably 35 formed from metal which formerly extended outwardly from the sides of the base-plate—that is, they are preferably not cut out of the base, although one of these ears might be cut from the base, if desired, and both of them 40 might be if the base were sufficiently broad to accommodate their lengths. The construction shown is, however, the one preferred by me. Each of these roller-ears near its lower end is provided with a hole e, adapted to receive the journal of the roller R. Two small

securing-ears C are shown as extending upwardly from one edge of the base and at each side of the roller-ear E. Preferably from the opposite edge of the base extends upwardly an arm A, which is preferably considerably greater in size and extends much higher than the ears C. The roller-ear E' upon this side of the base is preferably cut from the lower portion of the arm A, forming the hole e', as clearly shown in Fig. 2. This arm A and also the base are shown as provided with holes G, adapted to receive screws or nails by which the frame may be secured to the trunk or other article for which it is intended. A sheet-metal ear if flat would be easily bent under 55 the strains of use, and in order to stiffen the ear and strengthen it to resist lateral strain I bend it on a line running upward to the base. This bend is preferably inward—that is, the center of the bend is nearer the center of the 60 base-plate than are the edges of the ear; but I do not limit myself in all cases to an inward bend. The bend extends upward to the base-plate, and the inward bend (shown in the drawings) extends up to and includes a portion of the base-plate, as clearly shown in Fig. 65. This inward bend may obviously take different forms; but I preferably dish the whole, or substantially the whole, ear inward, as shown in Figs. 1, 2, and 3.

The form of roller-frame shown in Figs. 4, 5, and 6 differs slightly from that shown in the other figures. In this form the upwardly-extending arm A and ears C have been omitted, although these might be employed in connection with this form, if desired. These might also be omitted in connection with the forms shown in Figs. 1, 2, and 3, if desired. The roller-ears E of this second form are dished in the same manner as those shown in 80 Figs. 1, 2, and 3. In addition they are strengthened by means of one or more narrow inward bends or corrugations F, preferably formed one at each side of the ear adjacent the points where the edges of the ear join or merge with the base. The axes of these corrugations extend across the line of juncture of ears and base, and consequently include a portion of each, as is clearly shown in Fig. 4. These corrugations or narrow inward bends 85

materially strengthen the roller-ears whether the ears are dished or flat and assist to prevent the bending of the ears from their normal position. The structure of the ears and 5 the position of the corrugations are clearly shown by Fig. 4, which shows the caster-frame in section upon the line 4 4 of Fig. 5.

I am aware that many variations from the constructions shown may be made without departing from my invention as claimed, and I therefore do not limit myself to the particular embodiments of my invention herein described and illustrated.

Having thus described my invention, what 15 I claim is—

1. A sheet-metal roller-frame having a base-plate and a pair of roller-ears integral with and extending downwardly from said base-plate, one or more of said ears having an inward bend extending up to and forming a concavity in said base-plate.

2. A sheet-metal roller-frame comprising a base-plate and a plurality of roller-ears extending downwardly from said base-plate, 25 said ears having holes for the reception of a roller-journal and one or more of the ears having an inward bend extending from its hole up to and forming a concavity in said base-plate.

3. A sheet-metal roller-frame having a base-plate and a side plate integral with said base-plate and extending upward at one side of the

same, and a downwardly-extending roller-ear at each of two opposite sides of said base-plate, one of said ears being integral with one 35 of said plates and cut out of the other plate.

4. A sheet-metal roller-frame having a base-plate and a side plate integral with said base-plate and extending upward at one side of the same, and a roller-ear integral with one of 40 said plates and cut out of the other plate and extending downwardly from said base-plate, and one or more upwardly-extending lugs on the opposite side of said base-plate.

5. A sheet-metal roller-frame comprising a 45 base, a roller-ear turned down centrally of each of two opposite sides thereof, an arm extending upwardly from one of said sides and joined to the base on both sides of the roller-ear, and one or more ears turned upward from 50 the opposite side of the base.

6. A sheet-metal roller-frame comprising a base, a roller-ear turned down centrally from each of two opposite sides thereof, and an arm extending upwardly from one of said sides 55 and joined to the base on both sides of the roller-ear which is located on that side.

Signed at Bristol this 3d day of September, 1903.

ALBERT L. SESSIONS.
